UNITED STATES PATENT OFFICE.

JAMES F. McDONNELL, OF LAKEWOOD, OHIO, ASSIGNOR OF ONE-HALF TO SANITARY BOTTLE WASHING COMPANY (LIMITED), OF CHICAGO, ILLINOIS, A CORPORATION OF ILLINOIS.

BOTTLE-SUPPORTING MEANS.

1,260,006.

Specification of Letters Patent. Patented Mar. 19, 1918.

Application filed June 29, 1916. Serial No. 106,587.

To all whom it may concern:

Be it known that I, JAMES F. McDONNELL, a citizen of the United States, and residing at Lakewood, in the county of Cuyahoga and 5 State of Ohio, have invented a certain new and useful Improvement in Bottle-Supporting Means, of which the following is a full, clear, and exact description, reference being had to the accompanying drawings.

10 This invention relates to bottle capping apparatus, and more particularly to an improved bottle supporting pad for use in apparatus of this character.

15 In machines of the kind wherewith my invention is intended for use it is necessary to provide a resilient or yielding bottle supporting means in order to obviate breakage of the bottles, and the importance of such a provision will become apparent when it is 20 explained that a pressure of approximately four hundred and fifty pounds is exerted upon the bottle at the moment of capping it, and under the most favorable circumstances, a certain amount of breakage is inevitable.

25 Heretofore solid rubber pads have been employed in machines of this kind for supporting the bottle and absorbing the shock during the capping operation. These rubber pads, however, are comparatively short 30 lived for they soon become distorted from the continual action of the capping apparatus transmitted to them through the bottles, and are cut by the glass of broken bottles that is deposited on them and then 35 forced into them by subsequent capping operations with the result that they crumble away about their central portions leaving a very uneven supporting surface and consequently sustaining the bottle at such an 40 angle with respect to the capping apparatus or mechanism that breakage is greatly increased. Furthermore, these rubber pads, especially after they become worn, provide lodging places for dirt and germs, thus producing 45 unsanitary bottling conditions.

It is the object of my invention to overcome the foregoing difficulties in a very economical and simple manner by substituting for the present solid rubber pad, a sanitary 50 composite pad consisting of a rubber cushion having its upper surface entirely protected by a substantial plate of metal and its central portion cut away so as to produce an air chamber or pocket beneath the 55 plate which will enhance the cushioning

function of the pad. This represents the present preferred embodiment of my invention, although it will be understood that the scope of the invention embraces all modifications which fall within the terms of the 60 annexed claims.

In the accompanying drawing, wherein similar reference characters designate corresponding parts throughout the several views, Figure 1 represents a fragmentary 65 sectional elevation of a bottle capping apparatus wherein is incorporated, the bottle supporting pad of my invention; Fig. 2 is a top perspective view, and Fig. 3 a bottom perspective view of my improved pad; and 70 Fig. 4 is an enlarged sectional detail thereof.

The apparatus is of standard design and consists, generally, of a supporting element 1 that extends laterally from a standard 2 which supports a bracket 3 some distance 75 above the element 1 and through which the capping device 4 reciprocates. Extending from the standard 2, and spaced a short distance above the element 1, is a member 5 which embraces the bottle 6 and carries it 80 about the machine, within the guard 7 that is supported from a stationary table 8, it being understood that the element 1, the member 5, and the bracket 3 are carried by and rotate with the standard 2. These parts 85 constitute no part of my invention, and are common in standard types of bottle capping machines. It is deemed unnecessary, therefore, to go into further detail in the description of the apparatus, except to say that the 90 element 1 is surmounted by a plate 9 having apertures 10 for the reception of bottle supporting pads, one for the support of each bottle. In some machines the pad receiving apertures are straight sided, although in 95 the apparatus wherewith I have elected to show my improved pad, the sides of the apertures are flared downward and outward, and the pad is made of a corresponding shape to interlock within the aperture. 100

The pad comprises, in its present preferred form, an annulus 15 of resilient material, such as rubber, and a circular plate 16 is secured to its upper side by rivets 17 that are countersunk within the plate, as 105 shown in Fig. 4, and have flat heads 18 which repose within recesses 19 in the bottom of the annulus, the heads being spaced upward some distance from the bottom surface of the pad so as to allow the pad to 110

yield sufficiently to properly perform its function. When the pad occupies its recess in the supporting element (of which the plate 9 may be considered a part) the upper 5 surface of the plate 16 is substantially flush with the corresponding surface of the supporting element, and the space between the plate 16 and the bottom wall of the recess and surrounded by the annulus 15, constitutes an air chamber 20 which acts to increase the cushioning function of the pad 10 during the bottle capping operation.

It will be seen from the foregoing description of the construction of my improved 15 bottle supporting pad, that the part susceptible to any appreciable amount of wear is thoroughly protected as it is entirely contained within the recess of the supporting element and covered by the plate 16. The 20 fact that the cushion or resilient portion of the pad is of slight cross sectional area (the central portion being cut away as above described) prevents the pad from becoming distorted by its central portion being unduly 25 compressed by continuous use. In the ordinary solid rubber pads hereinbefore referred to, the distortion is considerably due to the fact that the density of the central portion of the pad is increased by the continual action of the capping apparatus transmitted to it through the bottle. Of course, 30 in connection with this course, the pad is further deformed by being cut away by glass deposited on it in the breakage of the 35 bottles.

Experiences of this kind are impossible with the bottle supporting pad herein disclosed, thus insuring prolonged usefulness; less breakage of bottles; and requires less attention on the part of the operator of the 40 machine. Also they are more sanitary than the ordinary form of pad, as has already been explained. In view of the foregoing facts, and the fact that considerable rubber 45 is saved in the production of my improved pads as compared with the former varieties, the improved pad has a great economical advantage over the pads of prevailing types.

Having thus described my invention, what

50 I claim is:—

1. In a bottle capping apparatus, the combination of a capping device, a bottle supporting element, a bottle supporting plate and an air cushioning device between said 55 element and said plate for the purpose described.

2. In apparatus of the character set forth, the combination of a supporting element, a bottle supporting plate, and a resilient mem-

ber interposed between said plate and the 60 supporting element and inclosing an air chamber beneath said plate.

3. In a bottle capping apparatus, the combination of a capping device, a rigid bottle supporting plate, a second supporting plate 65 carried by said first plate and cushioning means between said plates comprising an annular resilient member, said plates forming with said member a sealed air chamber, for the purpose described. 70

4. In apparatus of the character set forth, the combination of a supporting element having a recess, a pad of resilient material within said recess, the central portion of said pad being cut away to produce with 75 said element an air chamber, and a plate superimposed upon said pad and bridging the opening therein.

5. In a bottle capping apparatus, the combination of a capping device, a bottle supporting element, a non-yielding bottle supporting disk superposed thereover, the capping device being in alignment with the center of said disk and cushioning means located between said element and the periphery of said disk, said cushioning means comprising an annular resilient member whereby said cushioning means is free from the direct blows delivered to the center of said disk. 80 85 90

6. In apparatus of the character set forth, the combination of a supporting element having a recess the side walls whereof diverge from the open side of the recess, a pad within said recess and having its outer edge 95 flared to interlock with the side walls of the recess, and a metallic plate applied to the outer surface of the pad, the central portion of said pad being cut away to produce an air cushion beneath said plate. 100

7. As a new article of manufacture for use in bottle capping apparatus, a bottle supporting device comprising a supporting element, a supporting plate located above said element, and an annular pad of resilient material superimposed on said element and supporting said plate, said plate bridging the opening in said resilient pad. 105

8. As an article of manufacture for use in bottle capping apparatus, a bottle supporting device comprising an annular pad of resilient material, a supporting plate resting thereon, and means attaching said plate and said pad together, said plate bridging the opening in said annular pad. 110 115

In testimony whereof, I hereunto affix my signature.

JAMES F. McDONNELL.
